[57] CLAIM

The ornamental design for an expanded panel of extruded metal, substantially as shown and described.

DESCRIPTION

FIG. 1 is a plan view of the panel;
FIG. 2 is a fragmentary enlarged view of portion of the panel showing configuration thereof in greater detail;
FIG. 3 is a section taken on line 3—3 of FIG. 2 and drawn to a still further enlarged scale; and
FIG. 4 is a section taken on line 4—4 of FIG. 2 and shown to a further enlarged scale.
